UNITED STATES PATENT OFFICE

1,922,048

AIR-EXCLUDING AND AUTOMATIC
DRAINAGE DEVICEJens Peter Jacobsen, Lyngby, Denmark, assignor
to Standard Brands Incorporated, New York,
N. Y., a Corporation of Delaware

Application August 18, 1931. Serial No. 557,859

16 Claims. (Cl. 99—2)

My invention relates to a device which will serve normally to exclude air and its possibly associated impurities and moisture from entry to a chamber where the presence of the same might be detrimental, and which will serve also, automatically, to permit the free escape from said chamber of any substantial quantity of water or other liquid materials which may gain entry to such chamber.

10 My invention more particularly relates to a combination of a device having these general functions with an apparatus adapted for the irradiation of liquid materials. Such a combination (as will be apparent from the detailed description of my invention and its operation herein-after given) possesses certain distinct advantages in the maintenance of apparatus of this character in satisfactory continued operation. It also 15 protects the apparatus against the possible damage which otherwise might occur in the event of accidents, such as breakage of some portions of the apparatus.

20 A general object of my invention is to provide means for excluding the air with its possible accompanying contaminations (such as suspended solid particles and variable quantities of moisture) from the interior of apparatus where the presence of dust or other solid particles and excessive moisture might be detrimental, while at 25 the same time providing means for automatically permitting free and immediate drainage of liquid from such apparatus in case of the presence or accumulation of liquid in the apparatus.

30 One particular object and use of the invention is in connection with the protection of delicate parts, such for example as electrical devices employed in apparatus used for treating liquids, or suspensions of yeast or other solid substances in aqueous or other liquids, with ultra-violet rays 35 from a mercury vapor quartz lamp, from damage which otherwise might occur from the action of liquid material in the event of breakage of the transparent quartz or like frangible material separating the liquid under treatment from such electrical devices, while at the same time normally excluding atmospheric air with its possibly accompanying dust or other suspended particles and moisture from the apparatus.

40 45 50 The various objects and advantages of my invention will in part be obvious and will in part be further set forth in connection with the following particular description of a specific preferred embodiment of the invention as shown by the accompanying drawings, in which:—

Figure 1 is a side view of the exterior of the device;

Figure 2 is a vertical sectional view of the device looking in the same direction as in Figure 1;

Figure 3 is a vertical sectional view of the 60 device at right angles to the view shown in Fig. 2;

Figure 4 is a plan view of the device;

Figure 5 is a horizontal sectional view taken on the line 5—5 of Figure 2; and

Figure 6 is a view partly in section and partly 65 in side elevation of portions of an apparatus adapted for irradiation of liquid materials showing the device constituting a main feature of my invention in combination therewith.

70 In the drawings 1 represents a cylindrical casting or cylinder formed of brass or any other suitable or convenient material which may be provided at its upper end with screw threads 2 for attachment to the apparatus in connection with which the device is to be used. The lower end of the cylinder 1 may be faced off smoothly as at 3 and provided with a closely fitting closure plate 4 which may be formed of brass or other suitable material and which is adapted to make substantially gas-tight and liquid-tight engagement with the lower end of the cylinder 1.

75 The cylinder 1 is provided with a stud 5 projecting inwardly from its wall and having a notch 6 on its upper side preferably located approximately in the axis of the cylinder. A safety link 7 which in the particular construction illustrated may be in the form of a blotting paper disc provided with two eyelets 8 and 9 is positioned 80 with its upper eyelet engaging the notch 6 of the stud 5, while engaging the lower eyelet 9 is a spring 10, the lower end of which spring in turn engages the pin 11 which may be screw-threaded as shown at 12 and by this means and by its head 13 exterior of the disc 4 may serve 85 normally in cooperation with the spring 10 to retain the disc 4 firmly in position against the lower end of the cylinder 1.

90 To prevent rotation of the disc 4 the latter may be provided with an upstanding stud or pin 100 14 adapted to be positioned between two pins 15 extending inwardly from the wall of the cylinder 1 near its lower end as shown in Figures 2, 3, 4 and 5.

95 100 105 To provide against possible misplacement of the disc 4 when not closing the cylinder 1, a chain 16 may be provided having its respective ends attached to the cylinder 1 and to the disc 4 by any convenient means such as brackets 17 and 18.

110

Fig. 6 illustrates my invention as it comprises the combination of a device such as I have already described and as is shown in Figures 1 to 5 inclusive of the drawings together with certain portions of an apparatus adapted for irradiation of liquids and in this combination, as exemplified by the construction illustrated in Figure 6, the cylinder 1 is attached by means of screw threads at its upper end to the bottom 19 of the chamber 20 of an irradiating apparatus provided with an annular chamber 21 through which liquid or liquid mixtures such as aqueous suspensions of yeast may be passed, the liquid being supplied to the chamber 21 by an inlet tube 22 and passing from the chamber 21 through an outlet tube 23. The central portions of the side walls of the chamber 21 are provided with openings 24 and 25 in which openings a tube of quartz 30 or other material (usually of a frangible nature) is mounted and within this tube a mercury vapor lamp 31 may be placed. In the operation of an apparatus comprising a combination of parts as exemplified by the construction shown in Figure 6, the liquid material in the chamber 21 will normally be excluded from the chamber 20 by reason of the mercury vapor lamp and its surrounding tube and associated parts making liquid-tight closure of the openings 24 and 25. If by reason of the breakage of the tubes or parts forming such closure liquid is permitted to escape or flow from the chamber 21 into the chamber 20 such liquid is prevented from accumulating in the chamber 20 and from causing possible damages to electrical devices (diagrammatically shown) 26 and 27, located in the chamber 20 and serving to assist in the control and proper operation of the mercury vapor lamp or like device, by reason of the fact that, through the operation of the device of my invention as described in connection with Figures 1 to 5 inclusive of the drawings, the closure disc 4 will be permitted (by the effect of moisture as by the first accumulation of liquid flowing from the chamber 20 into the tube 1) to fall from the tube 1 and afford a free and adequate drainage outlet for the liquid leaking or flowing from the chamber 21 into the chamber 20.

In the use of the device constituting my invention in its particular preferred and exemplary embodiment as hereinbefore described, the apparatus may be attached (as by means of the screw threads 2 cooperating with a threaded opening) to the bottom of an otherwise normally closed chamber or receptacle such as a casing within which may be located a mercury vapor quartz lamp surrounded in part at least by an annular chamber through which yeast in aqueous suspension or other liquid material may be passed for the purpose of irradiating the liquid and any associated suspended solids such as yeast which may be carried by the liquid.

In apparatus of this general character the outer casing to which the device constituting my invention may be attached is intended normally to contain no liquid, but serves primarily as a retaining casing for the mercury vapor quartz lamp or like device and associated electrical devices used in effecting irradiation of the liquid. However, accidental cracking or breakage of certain interior portions of the apparatus may permit escape of liquid material from the irradiating chamber, to which it is normally confined in the proper operation of the apparatus, and such escaping liquid may, if its immediate and ade-

quate drainage is not fully provided for, enter said casing and come into contact with various electrical devices therein associated with the mercury vapor quartz lamp and the like and cause damage to such devices.

Prior to my invention it has been recognized that such damage to the relatively expensive lamp and electrical connections and magnets, etc., might ensue from the action of liquid escaping from its normal path of flow through apparatus of the general character mentioned in case of the breakage of the quartz protecting tube casing enclosing the mercury vapor quartz lamp and for this purpose the casing or lamp chamber enclosing the interior portions of apparatus of this general character have heretofore been provided with drainage holes for permitting escape of liquid from such casing. Such mere provision of drainage holes however necessarily involves one or the other of two distinct disadvantages (a) if these drainage holes are sufficiently small to effect proper exclusion of atmospheric air with its possibly associated dust and other suspended particles and moisture under all situations in which the apparatus may be used, the holes may not be sufficiently large to permit liquid outflow with adequate rapidity to afford proper drainage when they are required to function for this purpose, and (b) if the drainage holes are sufficiently large to permit free and adequate outflow of liquid escaping into the casing as by accidental breakage or cracking of its associated parts then sufficient atmospheric air with associated moisture and dust particles, etc. will be likely to enter the apparatus to produce detrimental effects as by accumulating on quartz surfaces within the apparatus which by reason of their high temperature in operation may be damaged by absorption of dust particles, etc. from the atmospheric air if the latter is permitted to freely enter the casing.

In the operation of my device for the particular exemplary purpose described, both of the disadvantages incidental to the mere provision of the open drainage outlets are avoided as will be apparent from the detailed description of the operation of my device as illustrated in its preferred embodiment and as used for such exemplary purpose. In such use the disc 4 will normally be held in position as shown in the drawings so as to afford a substantially air-tight and liquid-tight closure for the lower or outlet end of the cylinder 1, the disc 4 being normally retained in this position by the action of the spring 10 which in this position will normally be under at least some slight and appropriate tension and by the cooperation with this spring of the associated parts 7, 5, 12 and 13 as will be obvious from Figure 3 and other figures of the drawings, serving, when so held, to exclude atmospheric air and its possibly associated vapors or suspended impurities from the casing to which the device is attached.

When, however, by reason of cracking or breakage of the liquid retaining parts, such as the interior lamp-enclosing quartz tube of an apparatus as specifically mentioned, liquid is permitted to flow into the casing to which the device made according to my invention is attached, such liquid flowing by gravity into the tube 1 and coming in contact with the disc 7 will, by reason of the fact that this disc is formed of blotting paper or other suitable material quickly deprived of its tensile strength by the absorption of mois-

ture, destroy the tensile strength of the disc immediately to such a degree that the disc 7 will be broken in two, such action being assisted by the tension of the spring 10 on the disc. The 5 breakage of the disc 7 will deprive the closure plate or disc 4 of its means of support against the lower end of the casing 1 so that the disc or plate 4 will immediately fall free from the cylinder 1 carrying with it the spring 11 and will 10 leave the cylinder 1 free to act as a drainage outlet for liquid from the chamber to which it is attached. The size of the drainage tube 1 will, of course, be proportioned to provide such drainage capacity as might be sufficient or desirable according to the possible requirements of any particular apparatus to which it is intended to be attached. Regardless of how large the size and 15 drainage capacity of the tube 1 may be, it will when normally closed by the plate 4 serve efficiently to exclude air and associated impurities or suspended particles and moisture from the casing or receptacle to which it may be attached as an emergency drainage outlet.

Since certain changes may be made in the 25 above construction and different embodiments of the invention could be made without departing from the scope thereof, it is intended that all matter contained in the above description or 30 shown in the accompanying drawings shall be interpreted as illustrative and not in a limiting sense.

It is also to be understood that the following 35 claims are intended to cover all of the generic and specific features of the invention herein described, and all statements of the scope of the invention which as a matter of language might be said to fall therebetween.

Having described my invention, what I claim as new and desire to secure by Letters Patent is:— 40 1. In a device of the character described, in combination, an outlet passage adapted to permit egress of liquid, a closure for said passage, and positive retaining means normally holding such closure in place, such retaining means comprising an element readily disrupted when wetted.

2. In a device of the character described, in combination, an outlet passage adapted to permit egress of liquid by gravity flow, a closure for said 50 passage, normally held in place substantially to exclude flow of liquids or gases therethrough, positive retaining means normally holding such closure in place, such retaining means comprising an element the tensile strength of which is capable of being suddenly diminished by the action 55 of water to such a degree as to render such element readily disruptable, and a tensioning member connected with said element and exerting sufficient tension thereon materially to assist disruption of said element when weakened under 60 the influence of moisture.

3. In a device of the character described, in combination, an outlet passage adapted to permit egress of liquid by gravity flow, a closure for said 65 passage, normally held in place substantially to exclude flow of liquids or gases therethrough, positive retaining means normally holding such closure in place, such retaining means comprising an element the tensile strength of which is capable 70 of being suddenly diminished by the action of water to such a degree as to render such element readily disruptable, and a spring connected with said element and exerting sufficient tension thereon materially to assist disruption of said element 75 when weakened under the influence of moisture.

4. In a device of the character described, in

combination, an outlet passage adapted to permit egress of liquid by gravity flow, a closure for said passage, normally held in place substantially to exclude flow of liquids or gases therethrough, positive retaining means normally holding such closure in place, such retaining means comprising an element the tensile strength of which is capable of being suddenly diminished by the action of water to such a degree as to render such element readily disruptable, and a spring normally held under tension between said element and said closure. 80

5. In a device of the character described, in combination, an outlet passage adapted to permit egress of liquid by gravity flow, a closure for said passage, normally held in place substantially to exclude flow of liquids or gases therethrough, positive retaining means normally holding such closure in place, such retaining means comprising an element the tensile strength of which is capable of being suddenly diminished by the action 90 of water to such a degree as to render such element readily disruptable, and a spring normally held under tension between said element and said closure, said closure being free to fall by gravity when released from the retaining force of 95 said element and spring.

6. In a safety device adapted to prevent accumulation of moisture in a chamber of chemical or other apparatus, in combination, a drainage tube adapted for attachment to the lower portion of the chamber, a closure for said drainage tube, adapted to normally prevent inflow of atmospheric air and associated moisture through said tube and means normally holding said closure in 100 position but capable of automatic release of said closure under the influence of moisture.

7. In a safety device adapted to prevent accumulation of moisture in a chamber of chemical or other apparatus, a drainage tube adapted for 105 attachment to the lower portion of the chamber, a closure for said drainage tube, adapted to normally prevent inflow of atmospheric air and associated moisture through said tube and means 110 normally holding said closure in position but capable of substantially instantaneous automatic release of said closure on contact with aqueous or other liquid.

8. In apparatus adapted for irradiation of liquids, the improvement which comprises a chamber for the liquid under treatment and an adjacent chamber separated from the liquid chamber by frangible material and containing devices liable to damage by contact with the liquid treated, in combination with automatic means including an element readily disrupted when wetted to exclude air from the last mentioned chamber during the normal operation of the apparatus and to permit free egress of liquid therefrom. 125

9. In a safety device adapted to prevent accumulation of moisture in a chamber of chemical or other apparatus, the improvement which comprises in combination a drainage tube adapted for attachment to the chamber, a closure for said 130 drainage tube and means normally holding said closure in position but capable of automatically releasing said closure when wetted. 135

10. In an apparatus adapted for irradiation of liquids, the improvement which comprises a chamber for the liquid undergoing treatment and an adjacent chamber separated from said liquid chamber by a frangible material and containing irradiating means in combination with an outlet passage adapted to permit egress of liquid, a 145 closure for said passage and positive retaining 150

means normally holding said closure in position, such retaining means comprising an element readily disrupted when wetted.

11. In a safety device adapted to prevent accumulation of liquid in a chamber of chemical or other apparatus, the combination comprising a drainage tube adapted for attachment to the chamber, a closure member for said drainage tube, a stud projecting inwardly from the wall of said tube, a safety link composed of absorbent material readily disrupted when wetted, positioned upon said stud and a spring attached to said closure member and said safety link.
12. In a safety device adapted to prevent accumulation of moisture in a chamber of chemical or other apparatus, the improvement which comprises in combination a closure and a closure retaining means including a safety link consisting of an absorbent material which is readily disrupted when wetted.
13. In a safety device adapted to prevent accumulation of moisture in a chamber of chemical or other apparatus, the improvement which comprises in combination a closure and a closure

retaining means including a safety link consisting of a blotting paper disk having a plurality of attachment means.

14. In a device of the character described, in combination, an outlet passage adapted to permit egress, a closure for said passage, and retaining means normally holding such closure in place, such retaining means comprising a readily disrupted element.

15. In a safety device adapted to prevent accumulation of moisture in a chamber of chemical or other apparatus, the improvement which comprises, in combination, a closure member, and a means normally holding said closure in position but capable of automatically releasing said closure when wetted.

16. In a safety device adapted to prevent accumulation of moisture in a chamber of chemical or other apparatus, the improvement which comprises, in combination, a closure, and a closure retaining means including a safety link consisting of a readily disrupted element.
